UNITED STATES PATENT OFFICE.

PLATO G. EMERY, OF CHICAGO, ILLINOIS.

SHADE.

No. 800,280.

Specification of Letters Patent.

Patented Sept. 26, 1905.

Original application filed October 3, 1900, Serial No. 31,895. Divided and this application filed January 26, 1903. Serial No. 140,573.

To all whom it may concern:

Be it known that I, PLATO G. EMERY, a citizen of the United States, residing at Chicago, in the county of Cook and State of Illinois, have invented certain new and useful Improvements in Shades, of which the following is a specification.

This invention relates to improvements in shades for windows, doors, and other openings of that type which are held under a constant upward tendency and guided on "squaring-cords," and the application is a division of my application filed October 3, 1900, Serial No. 31,895.

The object of the invention is to provide simple and improved means for frictionally holding the shade against its upward tendency.

A further object is to inclose the clamping means wholly within the shade-stick and construct it so that its tension will be overcome by force applied to raise and lower the shade in the usual manner.

In the accompanying drawings, Figure 1 illustrates my invention embodied in a window-shade and is shown partly in section. Fig. 2 is a longitudinal sectional view of a part of the shade-stick and showing the clamping device. Fig. 3 is a transverse sectional view on the line 3 3 of Fig. 2. Figs. 4 and 5 are detail views of parts shown in Figs. 2 and 3. Fig. 6 shows the clamping device located at one end of the stick, which is partly in section. Figs. 7 and 8 are transverse sectional views illustrating different ways in which the clamping device may be constructed.

Referring to the drawings, 10 designates the curtain of my improved shade, mounted on a spring-roller 11 in a window-frame 12, and provided with a hollow shade-stick 13, through which pass the squaring-cords 14. I have chosen to illustrate my invention in this manner for the purpose of convenience and as showing, perhaps, the principal form in which the invention will be used; but I do not restrict the invention to the use of a spring-roller for giving the shade an upward tendency nor to the use of separate squaring-cords having their ends attached to the frame at diagonally opposite points, as shown, and the shade may be mounted in a frame or casing of any suitable character for windows, doors, or other openings.

The shade-stick is preferably made in rectangular form in cross-section, as shown in Figs. 3, 7, and 8; but other forms can be used and the clamping device correspondingly shaped without departing from my invention.

The clamping device comprises a member 15 and a yielding member 16, located within the stick and held in a suitable manner against endwise movement. In Figs. 2 and 3 I have shown the member 15 supported by a removable plate 17, which is arranged to fit in an opening 18 in the stick and has its ends 19 struck up to rest within the stick upon the end walls of the opening and providing shoulders 20 to abut against said end walls, which form stops, preventing endwise movement of the plate. A pair of screws 21 have threaded engagement with the member 15 and are provided with radial flanges 22 intermediate of their ends for resting upon the plate 17, while their heads 23 are arranged in openings 24 in the plate. In this way the screws which carry the clamping member 15 are anchored to the plate 17, and they can be readily operated to adjust said clamping member without removing any of the parts. The yielding member is shown held against endwise movement by stop-lugs 25, struck down from the stick, and this member of the clamping device is constantly under tension of a spring 26, located between itself and the wall of the stick. I may use a leaf-spring, as shown in Fig. 2, or a coil-spring 26', as shown in Figs. 7 and 8, and more than one spring may be employed if necessary to provide sufficient tension.

The clamping device illustrated in Fig. 2 and just described is preferably located at or about the middle of the stick, and the adjustable member 15 is adjusted so that the tension of the clamping device will be sufficient to hold the shade against the upward tendency afforded by the spring-roller or other means. I may, however, locate the clamping device at any point in the shade-stick and employ one or more, as desired. In Fig. 6 I have shown a clamping device embodied with the cord-guide at the end of the stick. This clamping device is in all respects the same as that shown in Fig. 2; but the figure shows another way of securing the device in the stick. The cord-guide 27 is arranged in the

end of the stick and has a top plate 28 and a bottom plate 29 integral or otherwise connected therewith and projecting into the stick, with their ends 30 inwardly turned. The 5 clamping members are retained in place against endwise movement between the cord-guide and the ends of the top and bottom plates, and the screws for the adjustable members have their heads seated in openings in the 10 bottom plate 29, which in this respect corresponds to all intents and purposes with the plate 17 shown in Fig. 2. Openings 31 are provided in the stick, so that access can be had to the screws for adjusting the member 15. A 15 leaf-spring 26 is arranged between the yielding member 16 and the top plate 28, as in Fig. 2; but one or more coiled springs may be used. Instead of the two adjusting-screws shown in Figs. 2, 6 I may obviously use one screw at 20 the middle of the adjustable member or some other suitable adjusting device, and of course I may reverse the relative position of the members or arrange them side by side.

The clamping device may be constructed to 25 engage both of the cords, as shown in Fig. 3; but it will ordinarily be sufficient to clamp only one of the cords, and the clamping members may be constructed with this end in view. In Fig. 7 I have shown clamping members 15' 30 16' with their adjacent faces rabbeted, one deeper than the other, so that only the cord 14' will be clamped. In Fig. 8 I have also shown a construction for clamping one of the cords, the stick being divided by a partition 32 into 35 a compartment 33 for the cord 14 and a compartment 35, in which the other cord 14' and the clamping members 15 16 are located, these clamping members operating only upon the single cord 14'. Any of the clamping devices can be used with the divided stick.

The operation of the invention will be readily apparent from an inspection of the drawings, and it will be understood that the tension of the clamping device is regulated by 45 adjusting the member 15 to hold the shade against its upward tendency; but when force is applied to raise or lower the shade in the usual manner the tension of the clamping device will be overcome and permit adjustment 50 of the shade. The clamping device is concealed within the stick, and while it cannot be tampered with it is still arranged for easy adjustment by the proper persons. In this construction I dispense entirely with handles 55 or devices of any kind for releasing the clamping device, which greatly simplifies the construction and operation and also provides a restraining device which is not apt to get out of order through carelessness or unskilful handling. The use of a device of this character avoids the necessity of keeping the squaring-cords taut and giving the shade constant at-

tention for this purpose, and besides the wear on the cords and guides is greatly reduced.

In the construction of the invention as 65 shown in the drawings and heretofore described I have referred to the clamping devices as comprising a yielding member and an adjustable member; but I do not limit the invention to this specific construction and would 70 have it understood that I reserve the right to make all changes which fairly come within the scope of the invention.

Without limiting myself to the exact construction and arrangement of parts herein 75 shown and described, what I claim, and desire to secure by Letters Patent, is—

1. The combination of a shade having an upward tendency, a hollow shade-stick, squaring-cords passing through the stick for guiding the shade, and a constantly-acting handleless clamping device located within the stick and intermediate of its ends for clamping a cord.

2. The combination of a shade having an 85 upward tendency, a hollow shade-stick, squaring-cords passing through the stick for guiding the shade, and a handleless clamping device within the shade-stick and intermediate of its ends comprising a member constantly 90 engaging a cord.

3. The combination of a shade having an upward tendency, a hollow shade-stick, squaring-cords passing through the stick for guiding the shade, and a clamping device within 95 the shade-stick comprising an adjustable member and a yielding member constantly engaging a cord.

4. The combination of a shade having an upward tendency, a hollow shade-stick, squaring-cords passing through the stick for guiding the shade, a clamping device comprising a yielding member and an adjustable member, and means for adjusting said adjustable member.

5. The combination of a shade having an upward tendency, a hollow shade-stick, squaring-cords passing through the stick for guiding the shade, a clamping device comprising two members one of which is adjustable, a plate supported in an opening in the stick, and an adjusting device supported on the plate and acting on said adjustable member.

6. The combination of a shade having an upward tendency, a hollow shade-stick, squaring-cords passing through the stick for guiding the shade, and a clamping device within the stick comprising two members, and stops for preventing endwise displacement of said members.

7. The combination of a shade having an upward tendency, a hollow shade-stick, squaring-cords passing through the stick for guiding the shade, a clamping device within the

stick and comprising a yielding member and an adjustable member, means for adjusting said adjustable member, and means for preventing endwise displacement of said members.

5 8. The combination of a shade having an upward tendency, a hollow shade-stick divided longitudinally into two compartments, square-

ing-cords passing through said compartments, and a device comprising two clamping members acting on a cord for restraining the shade.
